2 SHEETS-SHEET 2.

UNITED STATES PATENT OFFICE.

JOSHUA J. JONES, OF PITTSBURGH, PENNSYLVANIA.

SAFETY DEVICE FOR ELEVATORS.

1,050,949.

Specification of Letters Patent. Patented Jan. 21, 1913.

Application filed May 5, 1910. Serial No. 559,559.

To all whom it may concern:

Be it known that I, JOSHUA J. JONES, a citizen of the United States, residing at Pittsburgh, in the county of Allegheny and 5 State of Pennsylvania, have invented new and useful Improvements in Safety Devices for Elevators, of which the following is a specification.

This invention relates to elevators and 10 the principal object of the invention is to provide an improved safety device for automatically stopping or checking the speed of an elevator car whenever the operator loses control of the car, and the car starts 15 to run away.

In the accompanying drawings; Figure 1 is a diagrammatic elevation of an elevator car showing my improvement applied thereto; Fig. 2 a side elevation on an enlarged 20 scale of one of the improved safety devices shown in Fig. 1; Fig. 3 a front elevation thereof; Fig. 4 a detail of construction employed in connection with the safety device; Fig. 5 a central sectional view of the automatic operating means for said safety device; and Fig. 6 a side elevation thereof.

According to the preferred form of my invention a suitable air compressor or pump 1 is secured to the under side of the elevator car 2, preferably one on each side adjacent to the elevator guides 3. As shown more clearly in Fig. 3 the compressor may be of the ordinary standard type comprising a piston 4 connected to a crank shaft 5 by connecting rod 6. On one end of the crank shaft 5 is secured a gear 7 adapted to mesh with a pinion 8 carried on one end of a supporting arm 9, the parts being so located that the pinion 8 is adapted to swing 35 into and out of mesh with a rack 10 secured to the usual guide rail 3.

The crank shaft 5 is supported in journals 12 and on the shaft intermediate the gear 7 and one of said journals the supporting arm 9 is mounted. On the under side of the car, rearwardly of the compressor 1 is secured a spring cage 13 containing a heavy coil spring 16 adapted to act on a rod 14 having a forked end for engagement with a projecting end of the pinion shaft 15, as shown in detail in Fig. 4. The spring 16 tends to pull up on the rod 14 and thereby effect the rotation of the arm 9 so as to bring the pinion 8 into mesh with the 55 rack 10.

The arm 9 is provided with an operating

lever 17, the outer end of which is connected by means of a small flexible cable 18 passing over guide pulleys 19 and 20 respectively, to a point on the main supporting cables 21 of the elevator car. This cable 18 may be connected directly to the car cables, but preferably a carrying device is provided such as shown in detail in Figs. 5 and 6 and comprising an outer casing 22 60 adapted to be firmly fastened to the car cables 21, an inner casing 23, and a coil spring 24 interposed between the two casings and tending to push the casing 23 out of the casing 22. The safety cable 18 passes over a pin 25 carried by the casing 23 and normally the casing 23 is held in position within the casing 22 against the tension of the spring 24 by means of a trip arm 26, one end of which is adapted to project out 65 under the base of the casing 23 and the other end of which is normally in engagement with a pin 27 mounted on a pivoted lever 28, so that when the trip arm 26 engages the pin 27, the casing 23 is held within 70 the casing 22. The lever 28 projects out to the side of the car and is adapted to engage an obstruction 29 on a cable 30.

The compressors 1 are each provided with the usual inlet valve 31 and outlet valve 32 85 and the outlet passage 33 of each is connected to a common pipe 34 which may be extended up through the floor of the car and preferably is provided with a valve or cock 35 adapted to open or close communication through the pipe 34 or to vary the size of the outlet therethrough.

The cable 18 is normally pulled up so as to compress the spring and maintain the pinion out of engagement with the rack 10 95 as shown in Fig. 2, and during the ordinary running of the car the compressors remain inactive. Should the cables 21 break, the cable 18 is slackened and the spring 16 thereupon exerts its force to shift the pinion 8 into engagement with the rack 10. The compressor piston 4 is thereupon set 100 into motion and the compression of fluid takes place in proportion to the speed at which the car is descending. If it is desired that the car be brought to a complete stop, the outlet pipe 34 is maintained closed, but often the car will be stopped at a point intermediate two floors and in order to permit a certain control of the movement of 110 the car, the cock 35 may be manipulated to allow more or less exhaust of air from the

outlet pipe 34. It will be evident that by adjusting the cock to vary the outlet opening the car may be controlled as desired.

In addition to the automatic control of the car in case of the cables breaking, means are provided for setting the compressors into action when the speed of the car exceeds a certain desired degree. According to this means I make use of a governor arrangement heretofore employed in connection with elevators in which a cable running over sheaves at the top and bottom of the elevator shaft is adapted to operate a centrifugal governor, the governor being adapted upon the speed of the cable exceeding the desired degree to stop the movement of the cable. The cable 30 shown in Fig. 1 is such a cable and it will be seen that in case the speed of the car exceeds a certain degree the cable is stopped and the obstruction thereon then operates the lever 28 to trip the arm 26 and thereby permit the casing 23 to drop. The cable 18 is thus released and the compressor gears are thrown into action.

One compressor has its crank preferably set opposite to the other, so that there will always be one of the compressors pumping air at a time.

Having now described my invention, what I claim as new and desire to secure by Letters Patent, is:—

1. In a safety device for elevators, the combination with an elevator car, of a fluid compressor adapted to be operated by the momentum of the car and normally having its moving parts at rest, means for cutting the compressor into action, and a flexible connection operatively connected to the car operating cable for controlling said means.

2. In a safety device for elevators, the combination with an elevator car, of a fluid compressor carried by the car and adapted to be operated by the momentum thereof, a movable gear device permanently connected to said compressor, a rack located adjacent the car, a spring tending to throw said gear device into engagement with the rack, and a flexible connection attached to the car operating cable for normally maintaining said gear device out of engagement with the gear device out of engagement with the rack.

3. In a safety device for elevators, the combination with an elevator car and an operating cable therefor, of a fluid compressor carried by the car and adapted to be operated by the momentum thereof, a movable train of gears in permanent oper-

ative connection with the compressor, a rack mounted adjacent the elevator car, a spring tending to throw said gears into operative engagement with the rack, a lever for operating said gears, and a flexible cable connected to said lever and to the car operating cable and adapted to normally maintain the gears out of engagement with the rack against the tension of said spring.

4. In a safety device for elevators, the combination with an elevator car, of a fluid compressor adapted to be operated by the momentum of the car, a rack, a gear normally maintained out of engagement with said rack for operating said compressor and means governed by the speed of the car for effecting the engagement of the gear with the rack to thereby cut said compressor into action.

5. In a safety device for elevators, the combination with an elevator car, of a fluid compressor adapted to be operated by the momentum of the car, a transmission mechanism for imparting movement to the compressor, means normally maintaining said mechanism inactive, and a device operated upon excessive speed of the car for causing the transmission mechanism to operate, thereby operating said compressor.

6. In a safety device for elevators, the combination with an elevator car, of a fluid compressor adapted to be operated by the momentum of the car, mechanism for transmitting motion to said compressor, a member for throwing said mechanism into and out of action, a trip device normally maintaining said member in position with said mechanism out of action, and means governed by the speed of the car for controlling said member.

7. In a safety device for elevators, the combination with an elevator car, of a trip device comprising two members, an intermediate spring, and a trip lock device, normally holding said members together against the tension of the spring, a fluid compressor adapted to be set in motion by one of said members for effecting the retardation of the car, and means governed by the speed of the car for controlling said trip lock device.

In testimony whereof I have hereunto set my hand.

JOSHUA J. JONES.
